INVENTOR

BY

Geo. B. Wilcox

ATTORNEY

UNITED STATES PATENT OFFICE.

MERRILL M. WILCOX, OF SAGINAW, MICHIGAN.

TAPPET.

Application filed September 19, 1919. Serial No. 324,959.

To all whom it may concern:

Be it known that I, MERRILL M. Wilcox, a citizen of the United States, residing at Saginaw, in the county of Saginaw and 5 State of Michigan, have invented certain new and useful Improvements in Tappets; and I do hereby declare the following to be a full, clear, and exact description of the invention, such as will enable others skilled 10 in the art to which it appertains to make and use the same.

This invention relates to valve-actuating tappets for internal combustion engines, and pertains more particularly to certain 15 novel features of construction embodied in a multiple-piece valve tappet as a new article of manufacture, whereby I am enabled to produce an exceptionally light, but strong tappet, with a head of very hard metal such 20 as case-hardened steel to contact with the engine cam. A tappet of this kind also usually has an internal plug in the end opposite the head to receive the bolt or other adjustable device that contacts with the stem 25 of the valve. Preferred arrangements of such tappet plugs are shown and described and claimed in my co-pending applications constituting divisions of this present application.

30 The arrangement of parts in my improved tappet construction is such that they can be easily, quickly and accurately assembled and the individual parts can be manufactured at small cost and by automatic 35 machines of standard construction, insuring uniformity of size and shape and weight.

With the foregoing and certain other objects in view, which will appear later in the specification, my invention comprises the 40 devices described and claimed, and the equivalents thereof.

My invention is illustrated in the accompanying drawings, in which Fig. 1, is a central longitudinal section of a tappet, in 45 working relation to an engine cam, the end plug being removed.

Fig. 2 is a side view of a preferred form of tappet head.

50 Figs. 3 and 4 are similar views showing modified forms of the tappet head.

As is clearly shown in the drawings, the tappet consists of a body 1, which is preferably formed by boring a solid bar of metal to form a thin-walled tube; or the body may 55 be formed of sheet metal rolled to the form

of a tube, or by drawing and pressing from a flat sheet of metal, or by using a short piece of tubing of proper diameter and thickness.

Secured to the body 1 at one end is a head 60 member 2, formed of a separate piece of metal, heat-treated and hardened. The head 2 may be, and in practice is preferably formed with a laterally projecting flange 3, the face of which is preferably ground to 65 contact with the cam 4 of the engine, as shown in Fig. 1.

An elongated axially projecting cylindrical shank 5 is formed on the head 2 and is accurately fitted to and preferably received 70 in the aperture of the body 1, to which it is secured by spot welding, as in Fig. 1; or by being threaded and screwed into place, as shown in Fig. 3; or by forming the shank with depressions 6, as indicated in Fig. 4, 75 and correspondingly swaging or depressing the metal of the apertured body thereinto. The foregoing are practical and well-known means of securing cylindrical members in shells, and may be employed in carrying out 80 my invention. I prefer in practice, however, to weld the shank 5 in the bore or aperture of body 1, as shown in Fig. 1.

By the means above described, I have produced a tappet of light weight and great 85 strength. The parts are adapted to be easily and economically manufactured by automatic machinery, and can be rapidly and accurately assembled either by semi-automatic machinery, or by hand.

90 The elongated shank 2, formed integral with the flange 3 provides a strong and rigid structure admirably suited to withstand the shocks of rapidly repeated contacts with the cam and the shank itself affords ample 95 transverse strength and anchorage for the lower end of shell 1. This will be understood from the fact that the cam during the first half of the lift of the tappet causes a strong sidewise thrust against the tappet, 100 forcing the tappet laterally against the guideway, in which the tappet slides up and down. If the shell of the tappet at the point where it enters the guideway has a thin wall, such wall will buckle when the 105 sidewise strain is brought upon it, distorting the tappet, causing it to run hard and finally stick in the guideway, putting the engine out of operation.

110 The elongated shank 5 of applicant's

hardened head is always in the guideway during the operation of the tappet and consequently the side thrust is withstood by that part of the shell which is reinforced by the long shank, avoiding the danger of distortion or making the tappet stick.

Having thus described my invention, what I claim and desire to secure by Letters Patent is:

1. A tappet for internal combustion engines comprising a hollow tubular body, an independent cam-contacting head of hardened material having an elongated axially projecting shank integral with said head, said shank received in and fixed to an end 15 of said body.

2. As an article of manufacture, a tappet for internal combustion engines comprising a hollow tubular body of substantially uniform external diameter throughout its 20 length, an independent cam-contacting head of hardened material and an elongated

cylindrical shank integral with said head, said shank received within said tubular body and fixed to one end thereof.

3. In a multiple piece tappet including 25 an apertured body, a cam-contacting head comprising a hardened face and an elongated axially projecting shank integral with said face, said shank received in the aperture of said body and fixed thereto. 30

4. A tappet including a tubular body, a cam-contacting head of hardened material, said head formed with an elongated cylindrical shank, said shank received within said body and fixed to one end thereof. 35

5. A tappet including a tubular body, a cam-contacting head of hardened material, said head formed with an elongated cylindrical shank, said shank received within said body and welded thereto. 40

In testimony whereof, I affix my signature.

MERRILL M. WILCOX.
